DESIGN FOR A COVER FOR FOOD RECEPTACLES

Deane C. Severance, Walnut Park, Calif.

Application August 20, 1945, Serial No. 121,504

Term of patent 3½ years

(Cl. D44—1)

To all whom it may concern:

Be it known that I, Deane C. Severance, a citizen of the United States, residing in Walnut Park, in the county of Los Angeles and State of California, have invented a new, original, and ornamental Design for a Cover for Food Receptacles, of which the following is a specification, reference being had to the accompanying drawing, forming part thereof.

Fig. 1 is a top perspective view of a cover for food receptacles, showing my new design.

Fig. 2 is an underneath perspective view.

Fig. 3 is a reduced plan view.

I claim:

The ornamental design for a cover for food receptacles, substantially as shown.

DEANE C. SEVERANCE.
